United States Patent

Des. 234,537
Patented Mar. 18, 1975

234,537

RADIO RECEIVER

Takeyoshi Kawano, Kyoto, Japan, assignor to Matsushita
Electric Industrial Co., Ltd., Osaka, Japan

Filed Aug. 22, 1973, Ser. No. 390,635

Claims priority, application Japan Apr. 11, 1973

Term of patent 14 years

Int. Cl. D14—03

U.S. Cl. D56—4 B

FIG. 1

FIG. 2

FIG. 3

FIG. 1 is a front, top and right side perspective view of a radio receiver showing my new design;

FIG. 2 is a rear, top and left side perspective view; and

FIG. 3 is a front, bottom and right side perspective view.

Portions of the drawings are shaded to indicate contrast in appearance, and a portion of FIG. 1 has been diagonally lined to indicate transparency.

I claim:

The ornamental design for a radio receiver, as shown and described.
